UNITED STATES PATENT OFFICE.

FREDERICK AUGUST DAECHSEL, OF OTTAWA, ONTARIO, CANADA, ASSIGNOR OF THREE-FOURTHS TO WILLIAM FREDERICK POWELL, OF OTTAWA, ONTARIO, CANADA.

FURNACE.

Application filed September 10, 1923. Serial No. 661,954.

To all whom it may concern:

Be it known that I, FREDERICK AUGUST DAECHSEL, a subject of the King of Great Britain, and resident of the city of Ottawa, in the Province of Ontario and Dominion of Canada, have invented certain new and useful Improvements in Furnaces, of which the following is a specification.

This invention relates to improvements in furnaces, and more particularly to furnaces connected with heating systems for dwellings, and the like.

The objects of the invention are to provide an improved furnace of this character more particularly adapted for hot water heating and in which any kind of fuel can be used with economical and satisfactory results.

Further objects are the provision of an economy fuel furnace in which a maximum of heat will be obtained with a minimum of fuel.

Still further objects are the provision of a furnace of this character in which the several parts will more satisfactorily perform the various functions required of them, and in which the several parts are readily accessible for examination and cleaning out.

Yet another object is the provision of a furnace of this character which can be readily adapted to an oil burner.

With the foregoing and other objects more fully described hereinafter in view, the invention consists essentially of a furnace embodying the several improvements as described in the present specification and illustrated by the accompanying drawings which form part of the same.

Referring now to the drawings in which like characters of reference indicate corresponding parts in each figure:

Figure 1 is a section on line 1—1 of Figure 2.

Figure 2 is a top plan view of the furnace.

Figure 3 is a section on line 3—3 of Figure 1.

Figure 4 is a plan view of the detachable revolvable top plate of the furnace.

Figure 5 is a plan view of the fixed apertured plate on which the top plate revolves.

Figure 6 is a section on line 6—6 of Figure 4.

Figure 7 is a vertical section through the hood, showing the cleaning door open. 55

Figure 8 is a front elevation of the hood with cleaning door closed.

Figure 9 is a front view of the hood with cleaning door showing the webs to prevent smoke leakage. 60

Figure 10 is a section on line 10—10 of Figure 9.

Figure 11 is a vertical section of the water tubes and header.

Figure 12 is a perspective detail of the smoke baffle. 65

Figure 13 is a vertical section through the baffle in position, with dotted lines showing its relation to the auxiliary flue opening 14. 70

Figure 14 is a detail of the cold water intake pipe connections.

Figure 15 is a similar view of the hot water discharge pipe connections.

Figure 16 is a further perspective detail 75 of the cold water intake pipe connections.

Figure 17 is a section on the line 17—17 of Figure 1.

Figure 18 is a sectional view of the base plate. 80

Figure 19 is a plan view of the base plate.

In the drawings, A indicates my improved furnace as a whole, comprising an outer casing or shell 10 within which is arranged an inner casing 11 provided with a water jacket 12, the water jacket and the outer casing being in spaced relationship to one another to form therebetween a chamber 13 for the waste products of combustion, including the smoke. 85

It will be noted in the above construction that the inner casing 11 with water jacket 12 do not extend the full length of the outer casing 10, but terminate adjacent the top of the latter on a line substantially at 95 the top of a main smoke outlet 14 formed in the outer casing. This construction, in combination with the water heating elements hereinafter more fully described, provides an empty space 9 in the top of the casing 10, and into which the products of combustion automatically ascend, their exit from 100

this chamber 9, as also hereinafter more fully described, being controlled by suitable damper and diverting means.

Turning now to the construction of the furnace, 14 is a flue opening in the casing 10 and communicating with the space or chamber 13 surrounding the inner water jacket casing 11. Suitably connected to the opening 14 is a smoke conduit 15, in turn connected to the main flue or smoke stack.

16 is a suitably formed base for the casing members, here shown in the form of a circular tray provided with an opening 17 which is designed when necessary or convenient, according to the fuel used, to be plugged, and on which the fire burns. Should the furnace be required to burn liquid fuel, the plug 19 can be removed from this base plate and an oil burner arranged therein.

The space 20 within the casing and above the base plate 16 constitutes the heating chamber provided with a fire door 21, and slidably operable and oppositely arranged ash doors 22 and 23.

24 are hot water tubes, a plurality of which are suspended from a header 25, in series of substantially circular formation one within the other, as more particularly illustrated in Figure 17.

This header 25 is of circular formation and is provided with a central opening 26, and is supported within the inner casing on one side by means of an arm 27 adapted to rest on water jacket 12 on the inside of the casing 10 at a point in line with the top of the smoke outlet 14. On the other side the header is supported by the hot water discharge pipe 29, connected thereto at 30 and extending outwardly through the casing 10, just above the top of the inner casing 11 and water jacket 12.

This construction, as aforementioned, leaves a space 9 in the top of the outer casing 10.

31 is a circular hood in the top of the furnace, registering with the central opening 26 in the header 25 and connected through a conduit 32 with the smoke stack 33, the conduit 32 being provided with suitable damper means 34, while the hood itself is provided with a slantwise opening 35 in the form of a manhole provided with a swingingly mounted cleaning door 36 provided with smoke baffle means 37 formed thereon to prevent a leakage of smoke when the door is closed.

38 is a suitable stop on the top of the hood to prevent this door, when opened, from swinging backwards beyond a certain point, while 39 are suitable lugs on the door adapted to form hand grips for opening the door.

Arranged to form a top for the casing 10 is a circular plate member 40 fixedly secured thereon and having a central open-

ing therein 41, formed with a suitable flange edge 42 adapted to receive therein the hood 31, and provided therearound with a plurality of spaced elongated openings 43, as more particularly illustrated in Figure 5.

On top of this plate and adapted to embrace the outer edges thereon, as shown in Figure 1 at 44, is a revolving top plate 45 formed with a central opening therein 46, through which extends the hood 31 and around which the plate is adapted to turn on suitable guideways 47 formed on the plates 40 and 45. This revolving and detachable top plate, as illustrated in Figure 4, and in addition to the central opening 46 adapted, as will be understood, to register with the opening 41 in the plate 40, and also with the opening 26 in the header 25, is provided with an inspection door 48, hingedly mounted at 49 and provided with side lugs 50 adapted to engage with thumbscrews on the plate 45, whereby the door is securely held in closed position. This door is formed substantially the same as the several openings 43 in the plate 40 and is thus, as the plate rotates, designed to register with each of these openings in turn, whereby the furnace can be inspected from the top to the bottom, and also cleaned at any point.

51 are spaced lugs on the revolving top 45, adapted to receive therebetween a bar or otherwise to start the rotation of the top should it become stuck in any way through non-usage.

From the foregoing it will be seen that I have provided a furnace with an outer casing having an auxiliary flue and a main flue both communicating with smoke stack 33, and that this casing is partly in spaced relationship to an inner casing or heating chamber 11 provided with water jacket means 12 therearound. The whole is designed to fit into a base plate.

Further, the top of the casing is provided with a suitably apertured plate designed to receive therein a revolving top provided with an inspection door adapted to register with the apertures in the fixed top plate. Through both the revolving plate and the top fixed plate extends centrally a flue hood forming a direct connection with the smoke stack and provided with suitable damper means therein, and also having a cleaning door with a smoke proof lid.

We will now refer more particularly to the hot water heating elements within the furnace casing, as above mentioned, and which have already been referred to as comprising a circular header 25 suitably supported within the heating chamber in spaced relationship to the top and provided with a central aperture 26 registering with the main flue or hood 31.

This header carries suspended therefrom a plurality of water tubes 24, circularly ar-

ranged in series, in spaced relationship to one another (see Figure 11). These tubes 24 are secured to and communicate at their upper ends with the header 25, and are 5 screw-threaded at their lower ends to engage with screw caps 52. This construction of detachable end caps for the tubes is a distinct advantage in enabling them to be readily cleaned when the usual deposit from 10 the water is formed therein.

53 are webs extending into the tubes 24 and adapted to register with the webs 54 in the header 25 and, as shown in Figure 11, so formed as to leave a space in the header between the webs sufficient for the water to circulate therebetween in restricted volume.

Referring still to Figure 11, 55 is the cold water supply pipe, the cold water being delivered through it into the header 25 on the 20 side remote from the discharge pipe 29, there to be directed by means of the webs 53 and 54 downwardly into the tubes, and then upwardly back to the header, and eventually to the discharge pipe 29. It will, therefore, be seen that the webs 53, in combination with the webs 54, provide a double circulation of the water in the tubes and header, without the provision of any additional space in the form of extra tubing. In other words, 25 with the combination of the webs with the header and tubes, the water is twice heated by the same operation that in furnaces of different construction only heats the water once.

35 As shown in Figures 14 and 16, the water supply pipe 55 is supplied from the main cold water supply pipe 56 through the branch 57, this main water supply pipe 56 being also provided with a second branch pipe 58, adapted to supply cold water to the jacket 12.

Having thus described the circulations and the cold water supply, reference to Figures 1 and 15 will illustrate the hot water discharge means, comprising the main discharge pipe 29 registering with the hot water pipe 59, shown in Figure 17, and connecting the series of tubes. The hot water main discharge pipe 29 is connected through a three way joint 60 with the supply pipe 61 to the radiators or the like, the other end of the joint 60 being connected to the hot water discharge pipe 62 from the jacket 12, whereby the hot water is discharged simultaneously from the header and the jacket to the heating system. 63 is a suitable drain for the hot water supply pipe.

In operation, and dealing with the heating arrangements apart from the water discharge and supply arrangements, on the fire being lighted the heat will ascend directly to heat the tubes and header, and will travel directly upwards to the auxiliary flue or hood 31 which, until the fire is well lighted, 60 is left open. On the fire becoming thor-

oughly lighted, the damper 34 is closed or partially closed, directing the heat and smoke backwards into the chamber 13, where they encounter suitable baffle means 64 arranged therein, and whereby they are diverted eventually to the main flue opening 14 into the main smoke stack 33.

Above mentioned smoke baffle means 64 is illustrated in Figures 12 and 13, and is provided in the outer heating chamber 13, preferably of inverted U shape and adapted to prevent smoke and heat units, when the main draft is closed, from flowing directly through the auxiliary flue 14, by diverting them down and around the chamber 13 to subsequently ascend and then pass outwardly through the main flue and finally into the smoke stack.

The essential features of my improved furnace will, from the foregoing, be seen to comprise the revolving top with an inspection door therein, in combination with the apertured top plate, the hood shaped flue registering with the opening in the header and thereby registering directly with the centre of the fire below the header, and tubes, whereby a direct draft is provided through the header and flue, thus enabling any sort of fuel to be quickly and satisfactorily lighted and consumed, and afterwards so regulated by means of the main flue 14 and the chamber 13 with baffle means therein that the heat generated can be utilized a second time by being diverted backwards, the water in the header tubes and water jacket being simultaneously subjected to the action of the fire.

Referring now to the water circulation, it will be seen that while the principle may not be altogether novel, I have so improved it by means of the webs or baffles in the header and tubes that it is possible with the same quantity of fuel as heretofore used, to obtain at least double the efficiency in the heating of the water.

It should here be mentioned that while the fire can be tended in the ordinary way through the fire door, wood or other fuel can also be supplied through the door 36 in the top flue or hood.

The inspection door, as previously mentioned, enables the several parts to be easily reached and repaired and cleaned, communicating as it does in turn with the parts of the furnace by means of the apertured top plate thereon.

As many changes could be made in the above construction and many apparently widely different embodiments of my invention, within the scope of the claims, constructed without departing from the spirit or scope thereof, it is intended that all matter contained in the accompanying specification and drawings shall be interpreted as illustrative and not in a limiting sense.

What I claim as my invention is:

1. A furnace comprising an outer casing, and an inner casing provided with a water jacket and spaced from the outer casing, and 5 adapted, in combination, to form inner and outer heating chambers, a top plate provided with a plurality of openings for the outer casing, a detachable and rotatably mounted cover adapted to fit on said top 10 plate and having door means therein designed to register with each of the openings in the top plate, auxiliary flue means through said top plate and cover, damper means for said auxiliary flue means, water 15 heating elements in the inner chamber, and water intake and discharge means connected to said water heating elements and to the water jacket, a main flue communicating with the outer chamber, and baffle means 20 for said flue.

2. A furnace comprising an outer heating chamber, and an inner heating chamber provided with a water jacket, an apertured top plate having a plurality of openings and 25 a revolving cover formed with an inspection door adapted to fit on said plate, water heating means in the inner heating chamber, water intake and discharge means for said heating means and water jacket, an auxiliary flue through said top plate and cover, 30 damper means for said flue, a main flue means communicating with the outer heating chamber, and means for directing the heat units into said chamber, and baffle 35 means in said chamber in combination with the main flue.

3. A furnace of the character described, comprising an outer casing, and a heating chamber provided with a water jacket 40 adapted to form with said outer casing a second or outer heating chamber, a detachable revolving top with openings therein for the furnace, auxiliary flue means there-through, a main flue for the outer heating 45 chamber, means for directing the flow of heat units and smoke from the auxiliary flue to said outer chamber and then to the main flue, water heating means in the inner chamber, cold water intake and hot water dis- 50 charge means connected to said water heating means and to the water jacket, whereby water is circulated through the heating elements and water jacket simultaneously.

4. In a furnace of the character described 55 and in combination, an outer casing, and an inner casing provided with a water jacket and spaced from the outer casing, and ex-tending to adjacent the top of the outer casing, whereby an inner heating chamber and 60 an outer heating chamber of lesser length than the outer casing are provided, a top plate having openings therein for the outer casing and a revolving top having an inspection door therein and adapted to fit on said 65 top plate, an auxiliary flue through said

cover and plate, fluid heating elements across the top of said chambers and extending into the inner chamber and having a central opening registering with the auxiliary flue, a main flue through the outer casing and communicating with the outer heating chamber adjacent the top thereof, damper means in the main flue whereby, in combination with baffle means for the main flue, the smoke and heat units are directed from 70 above said chambers into the outer chamber and into the main flue. 75

5. In a furnace of the character described and in combination, an outer casing, and an inner casing provided with a water jacket 80 and in spaced relationship to the outer casing, said inner casing being of lesser length than the outer casing, whereby, in combination with said outer casing, an inner heating chamber and an outer heating chamber are provided, a fixed top plate for the outer casing having a plurality of apertures therein and a central aperture adapted to receive an auxiliary flue, a revolving cover adapted to fit on the top plate and provided with a central aperture to receive the auxiliary flue, inspection means in the cover, and damper 85 means for the flue, and cleaning door means in said flue, and smoke confining webs on said door, a circular header having a central opening therein registering with the main flue and supported across the top of the inner chamber, a plurality of water tubes suspended in said header, cold water intake and 90 hot water discharge means communicating with opposite sides of the header and the water jacket respectively, a main flue in the top side of the outer heating chamber and extending through the outer casing to connect with the auxiliary flue, baffle means for 95 said flue whereby, in combination with the damper means in the auxiliary flue, the heat units and the smoke are diverted to the outer chamber and then to the main flue. 100

6. In a furnace of the character described 105 and in combination, an outer casing, and an inner casing provided with a water jacket and spaced from the outer casing to form outer and inner heating chambers extending 110 partially the length of the outer casing whereby a space is provided in the outer casing above said chambers, a revolving top for the outer casing, main damper means for the outer chamber through the casing side fluid, heating elements comprising a centrally apertured header having a plurality 115 of water tubes suspended therefrom for the inner chamber, and water intake and discharge means connected to opposite sides of said header and to the water jacket, web baffle means in said tubes and said header, and smoke baffle means for the main flue. 120

7. In a furnace of the character described 125 the combination with an outer casing pro- 130 vided with a top plate having a plurality of

- apertures therein and a revolving cover formed with inspection means, adapted to register individually with the apertures in said top plate, said plate and cover having
- 5 an auxiliary flue extending therethrough, of an inner casing substantially shorter than the outer casing and provided with a water jacket in spaced relationship to the outer casing, whereby an inner heating chamber
- 10 and an outer heating chamber are provided, a main flue in the side of the outer casing communicating with said outer chamber, and smoke baffle means for said flue, a water header across the top of said chamber, a plurality of water tubes suspended therefrom within the inner chamber, webs formed in said tubes and webs formed in said header designed to register in spaced relationship with the webs in the tubes, water intake and
- 20 discharge pipes connected to the header and to the water jacket at opposite sides thereon, and damper means for the auxiliary flue.
- 15 8. A furnace of the character described comprising, in combination, an outer casing, and an inner casing spaced therefrom and provided with a water jacket and designed to form, in combination with the outer casing, an inner chamber and an outer chamber of substantially lesser length than the outer
- 25 casing, revolving top means for the furnace adapted, in combination with a fixed apertured top plate provided with a plurality of apertures and inspection means in the cover, to provide cleaning and inspection means for
- 30 the furnace, an auxiliary flue through the top plate and cover, damper means for said flue, a main flue communicating with the outer chamber and arranged at right angles to the auxiliary flue, smoke baffle means in
- 35 the outer chamber for said main flue, fluid heating elements in the inner chamber comprising a circular header having a plurality of circularly arranged water tubes suspended therefrom, and means for supporting the header across the top of said chambers, whereby a space is provided between the header and the revolving top, water baffle means in said tubes and header, and detachable screw cap means for the outer ends of
- 40 said tubes, and cold water intake and hot water discharge means connected to said header and to the water jacket.
- 45 9. A furnace of the character described comprising, in combination, an outer casing, and an inner casing provided with a water jacket and spaced from the outer casing to form in combination therewith an inner chamber and an outer chamber of substantially lesser length than the outer casing, a recessed base plate for said casing, and a fire plate in said base, a header for the inner chamber, and means for supporting the header across the top of said chambers, a plurality of water tubes suspended from said header, water baffle means in said tubes and
- 50 said header, and a central opening in the header, a top plate with openings therein for the furnace, an auxiliary flue extending therethrough, and a revolving cover adapted to fit into said plate and to rotate around said flue, said flue registering with the central opening in the header, damper means for the flue, a main flue through the side of the outer casing, and communicating with the outer chamber adjacent the top thereof, and baffle means for said flue, whereby on the auxiliary flue damper means being operated the heat units from the inner chamber are diverted to the outer chamber and then to said main flue.
- 55 10. In a furnace of the character described, the combination, with an outer casing, of an inner heating chamber provided with a water jacket and spaced from said outer casing to form an outer heating chamber, said chamber being substantially of lesser length than said casing, a top plate with a plurality of openings therein for the casing and a rotatable cover with inspection means therein for said top plate, an auxiliary flue extending through the top plate and cover, a header supported across the top of the inner chamber and formed with a central opening having a plurality of water tubes arranged in spaced series therearound, web baffle means in said tubes and header, and water intake and discharge means connected to the header and the water jacket, a main flue for the outer chamber, and smoke baffle means for said flue, whereby on the smoke and heat units being diverted from the auxiliary flue they will circulate through the outer chamber and into the main flue.
- 60 11. In a furnace of the character described, the combination with an outer casing and a suitable base having a top plate and a revolving cover plate, and an auxiliary flue through said plates, of an inner casing provided with a water jacket and adapted to form, in combination with the outer casing, an inner heating chamber and an outer heating chamber on each side of the water jacket, and of substantially lesser length than the outer casing, a header across the top of said chambers, and fluid heating elements from said header suspended within the inner chamber, whereby, in combination with the fire therein, the water in said elements and the water jacket is heated, a main flue through the side of the casing, and communicating with the outer chamber, and smoke baffle means for said flue, damper means in the auxiliary flue adapted to divert the heat units and smoke to the outer chamber whereby the water in the water jacket is again heated, an inspection door in said cover and a plurality of apertures adapted to register individually with said door in the top plate, and cleaning door means in the auxiliary flue, cold water intake means connected to the header and the water jacket,
- 65 70 75 80 85 90 95 100 105 110 115 120 125 130

hot water discharge means for the opposite side of the header, and hot water intake means connected to the water jacket, whereby the water circulates through the header and the water jacket to the heating coils and from the heating coils back to the water jacket.

In witness whereof I have hereunto set my hand in the presence of two witnesses.

FREDERICK AUGUST DAECHSEL.
